TOOTHBRUSH

Murray Schotland, New York, N. Y.

Application April 28, 1953, Serial No. 24,718

Term of patent 14 years

(Cl. D9—2)

To all whom it may concern:

Be it known that I, Murray Schotland, a citizen of the United States, residing in New York city, in the county of New York, and State of New York, have invented a new, original, and ornamental Design for a Tooth Brush, of which the following is a specification, reference being had to the accompanying drawing, forming part thereof.

Fig. 1 is a top view of a tooth brush, showing my new design,

Fig. 2 is a side view thereof;

Fig. 3 is a bottom view thereof;

Fig. 4 is a sectional view of the tooth brush shown in Fig. 1, and taken on line 4—4 thereof;

Fig. 5 is another sectional view of the tooth

brush shown in Fig. 1 and taken on line 5—5 thereof, and

Fig. 6 is an enlarged fragmentary top view of the tooth brush shown in Fig. 1, illustrating the ornamental grooved detail and the configuration thereof.

I claim:

The ornamental design for a toothbrush, substantially as shown and described.
